UNITED STATES PATENT OFFICE.

OTTO EICK, OF ST. LOUIS, MISSOURI.

DESIGN FOR A RUBBER BRUSH.

44,436.

Specification for Design.

Patented Aug. 5, 1913.

Application filed March 18, 1913. Serial No. 755,252. Term of patent 14 years.

To all whom it may concern:

Be it known that I, Otto Eick, a citizen of the United States, and a resident of St. Louis, in the State of Missouri, have invented a new, original, and ornamental Design for Rubber Brushes, of which the following is a specification, reference being had to the accompanying drawing, forming part thereof.

The drawing is a perspective view of the brush.

I claim:

The ornamental design for a rubber brush, as shown.

OTTO EICK.

Witnesses:

SYDNEY EICK,
W. W. GALEN.
